UNITED STATES PATENT OFFICE

OSCAR M. PANNIER, OF PITTSBURGH, PENNSYLVANIA, ASSIGNOR TO PANNIER BROS.
STAMP COMPANY, INC., OF PITTSBURGH, PENNSYLVANIA, A CORPORATION OF PENN-
SYLVANIA

METALLIC TAG STRIP

Application filed July 16, 1928. Serial No. 293,046.

This invention relates to a metallic tag strip.

Previously metallic tags have been sheared to length as a preliminary to performing an embossing operation thereon, such sheared lengths being then fed one at a time to the embossing machine in which their proper positioning presents no problem.

In feeding metallic strips to an embossing machine to be acted upon thereby, considerable difficulty has been experienced in positioning a suitable length of a continuous strip in the machine and in shearing off the proper length which has been embossed, and results in a great loss of time to the operator of the machine.

In rolling strips of zinc, aluminum, and other metals suitable for use in embossed tags, the metal is rolled down to the desired gauge in long strips with the grain of the metal extending longitudinally thereof. If then these strips are to be fed to a punching machine and cut into tags to be fed individually to an embossing machine, it is practically necessary to punch out the tags transversely of the strip, with the grain of the metal extending transversely of each individual tag. This is for the reason that these punching machines operate at a great speed, and if the tags were cut longitudinally of the strip, a great deal of time and attention would be required in supplying new strips.

When the grain of the metal runs transversely of the tags, such graining may cause any individual tag, particularly when subjected to a relatively low temperature, to be accidentally broken on any transverse line throughout the length of the tag. If, however, the relatively wide metallic strips be sub-divided longitudinally into narrower strips of the desired width for the tag, thus retaining the longitudinal graining of the metal, the tensile strength of the metal is preserved throughout the length of such narrow strip, and each sub-division thereof.

An object of the present invention is to provide a strip of a suitable metal, such as zinc, aluminum, or tin, which is so arranged that the lengths of the strip which constitute the separate tags may be readily broken off after they have been embossed or otherwise marked with the desired characters.

Another object of the invention is to provide a metallic tag strip having the desirable characteristics above noted which also facilitates the operation of embossing, or otherwise marking, the tags, in that the strip as a whole may be passed through the machine for embossing, or otherwise marking, the tags.

Another object of the invention is to so graduate the weakening of the strip which permits such ready breakage, that the strip retains throughout its length sufficient coherence to permit it to be wound on a reel or spool for feeding it to the machine.

Figure I is a plan view illustrating the feed plate of an embossing machine and a tag strip with one section thereof positioned to be acted upon by the machine; Figure II is a longitudinal sectional view, taken on the line III—III of Fig. I; Figure III is a fragmentary side elevation of a portion of the tag strip, showing the same on an enlarged scale to clearly illustrate the structure which facilitates separation of the sections by breakage; Figure IV is a plan view of a fragment of one of the wide strips or ribbons from which the tag strips are cut, indicating the lines along which the wide strip or ribbon is to be cut to form the tag strips; Figure IV^a shows a tag strip separated from the wide strip or ribbon, scored transversely, and notched; and Figure IV^b shows a tag strip embossed and spooled, with one tag separated from the strip. All of the views IV, IV^a, and IV^b indicate the graining of the metal and illustrate its extension longitudinally of the wide strip or ribbon, and longitudinally of each tag strip and individual tag.

In the drawings the tag strip is indicated generally by the reference letter A.

The various sections 3 of the strip A are marked off from each other by relatively deep scorings 4. As shown particularly in Figure III of the drawings, each of the scorings 4 extends through slightly less than half the thickness of the strip. This relationship applies to a strip of zinc alloy of a thickness suitable for spooling. With aluminum, or any aluminum alloy, the tensile strength of the metal is much greater, and the strip is desirably scored more deeply.

In order to further facilitate separation of individual tags from the strip, the metal of the strip may be cut through at the edges of the strip and in line with the scoring. In order that such cut edge may provide stop notches for the strip, a portion is desirably cut or punched out, as for instance to provide the bevel notches 5.

It will be understood that the original wide strips, or ribbons, may either be cut into strips of the desired tag width and subsequently scored, or may be first scored transversely and then cut into strips of the desired tag width. If the notching of the edges be desired, it may in either instance be performed during the punching operation.

Figures IV, IV^a and IV^b of the drawings illustrate generally stages in the manufacture and use of the tag strips. Thus in Figure IV the relatively wide strip or ribbon 11 is cut longitudinally along the lines X—X, the graining of the metal, indicated generally by the lines 12, extending longitudinally of the wide strip 11, the tag strip A, and the individual tags 3.

Figure IV^a shows the scorings 4 which extend transversely of each tag strip A for separation of the individual tags of the strip along the definite lines of scoring. Figure IV^a shows also the edge notches 5.

Figure IV^b illustrates the separation of a tag 3 from a tag strip A, which has been embossed with characters 13 and spooled, by an intentional flexing at the scoring 4 and notches 5 of a severity sufficient to effect separation.

In embossing metallic tags from the strip, the strip is drawn, from right to left in Figure I, either manually or by a gentle force mechanically applied. When a length or section 3 of the strip lies in the proper longitudinal position in feed groove 7 of feed plate 2 for an embossing operation thereon, the progress of the strip is arrested. This arrest of the strip is caused by engagement of stop pins 8 on the machine with the stop or weakening notches 5 in the edges of the strip.

After completion of the embossing operation, the strip is drawn forwardly so that the embossed section is removed from the feed plate, and the next succeeding section takes its place in the feed groove.

In order that a very moderate pressure may be sufficient to draw the notched portion of the strip past the stop pins, these pins are forced inwardly by relatively light springs 9, and are provided with rounded notch engaging ends 10.

After the various sections have been properly embossed, the strip may if so desired be again rolled on a spool, and the sections broken off to provide individual tags for separate use. It should be understood that the sections or tags may be broken off by hand, without the use of cutting or clamping tools.

The tag strip and cooperating machine of the present invention do away with the disadvantages naturally inherent in the use of metallic tag strips, and preserve all the natural advantages thereof. Also, the speed at which the successive embossing operations may be performed by this invention adds greatly to its desirability. It should be further understood that this effect is obtained by solving problems not inherent in the use of strips of fibrous material, such as paper, or pasteboard or paperboard.

What I claim is:

1. A metallic tag strip for use in metallic tags comprising a length of strip of a relatively soft metal provided with transverse scorings, the depth of such scoring being so regulated with respect to the thickness of the strip and tensile strength of the metal as to provide lines of weakness for ready division of the strip into separate tags by intentional action but leaving sufficient continuity of the metal of the strip to permit winding the same upon a spool of moderate diameter without severance of the tag sections.

2. The method of making metallic tags consisting in cutting a relatively soft rolled metal into strips with the grain of the metal disposed longitudinally of each strip, weakening the metal of the strip along lines transverse to the extension of the grain of the metal, such weakening being sufficient to permit of subsequent ready sub-division of the strip into separate tags along the lines of weakness while preserving sufficient thickness of the metal to permit spooling of the strip or folding thereof upon such lines of weakness, and impressing characters on the metal of the strip in the intervals between the lines of weakness.

3. The method of making metallic tags consisting in cutting a relatively soft rolled metal into strips with the grain of the metal disposed longitudinally of each strip, and weakening the metal of the strip along lines transverse to the extension of the grain of the metal, such weakening being sufficient to permit of subsequent ready sub-division of the strip into separate tags along the lines of weakness while preserving sufficient thickness of the metal to permit spooling of the strip.

4. A metallic tag strip comprising a length of relatively soft rolled metal with the grain of the metal extending longitudinally of the strip, said strip being scored at intervals transversely of the grain of the metal and the depth of the scoring being regulated with respect to the thickness of the strip and tensile strength of the metal to provide lines of weakness for ready division of the strip into separate tags by intentional action but to leave a sufficient thickness of the metal at the scorings to permit winding the strip upon a spool of moderate diameter without severance of the tag sections.

15 In witness whereof, I hereunto set my hand.

OSCAR M. PANNIER.
